GARMENT CONSTRUCTION

Murray Kay, New York, N. Y.

Application May 25, 1943; Serial No. 488,364

6 Claims. (Cl. 2-234)

This invention relates to improvements in garment construction, and particularly to an improved side placket closure for skirts, slacks, or the like.

An object of my invention is to provide improved means for closing a side opening of a garment trimly and snugly, without the use of "zipper" fastening means, buttons, or equivalent.

It is an object of my invention to provide a side closure for a garment, which does not embody fastening means, and provides a complete closure which will not expose the body or undergarments regardless of the posture of the wearer.

It is an object of the invention to provide an improved pocket construction for a garment, which combines the functions of a pocket and side closure for a garment.

It is an object of my invention to provide a side closure of the nature of a pocket which may be worn internally or externally while affording complete closure of the side opening of the garment.

It is an object of my invention to provide a side closure for a garment which prevents exposure of the body, while affording ventilation.

It is an object of the invention to provide a closure of the type aforesaid which may be employed with a drop seat garment.

An object of my invention is to provide a combined pocket and placket which may be used either internally or externally of the garment while affording in either position complete closure and protection at the side of the garment without side-fastenings, draw-strings, or the like, thereby saving material and manufacturing costs.

According to a preferred form of my invention, I construct the garment with a relatively conventional opening at the upper portion of either or both of the side seams thereof to permit the garment to be donned. The garment may be an individual skirt or slack, or may be intended for combination with a blouse to be buttoned thereto, as in a cover-all or work uniform. Slacks may be made with a drop seat if desired.

For association with the side opening of the garment, to close the same, I provide an improved frontispiece or shield which is a complete unit in itself, to be attached, at one edge, to the garment at the hemmed or taped placket of the side opening. Said shield may be a pocket, secured along one edge only, to but one of the hemmed or reinforced portions of the garment; the pocket is preferably of substantial depth and provided with

means at its upper portion for securement to the waist band of the garment.

The pocket may be worn either internally or externally of the garment, and in either circumstance affords a complete closure of the side opening, preventing any exposure of the body thereof.

By securing the shield or pocket to the side opening at only one side of the pocket, circulation of air is permitted between the garment and the unsecured portion of the shield, affording ventilation of the garment. The length of shield or pocket is preferably at least equal to the length of side opening, to afford complete concealment of body or undergarments.

Other features will be apparent from the following detailed description of the specific embodiments illustrated in the accompanying drawings.

In the accompanying drawings:

Fig. 1 is a view of one embodiment of my invention, as worn, with a portion of the slacks immediately in front of one of the side closure-pockets torn away to reveal said pocket;

Fig. 2 is a sectional view taken through 2-2 of Fig. 1 to show the relationship of the pocket with respect to other garment elements;

Fig. 3 is a rear view of the portion of the combined slacks and blouse garment, with the seat dropped to show the pocket construction;

Fig. 4 is a front view of the combined slack and blouse garment with the front panel of the garment dropped to show the manner in which the closure-pocket means overlaps said front portion to provide complete concealment of the body of the wearer at the side openings of the slacks;

Fig. 5 is a side elevation of the slack and blouse combination, with one of the side openings in position to reveal the relationship of the pocket thereto;

Fig. 6 is a section taken on the lines 6-6 of Fig. 5;

Fig. 7 is taken on lines 7-7 of Fig. 6 and discloses the relationship of the pocket with respect to the placket opening of the garment;

Fig. 8 is a skirt having my improved closure-pocket, said figure disclosing a second form of pocket;

Figs. 9 and 10 are sectional views respectively on lines 9-9 and 10-10 of Fig. 8 showing the relationship of the closure-pocket with respect to the garment;

Fig. 11 is a side elevation of a portion of the pocket structure showing its method of securement to the placket at the side opening of the garment;

Fig. 12 is a perspective of a skirt equipped with my improved closure-pocket, showing the position of the pocket when worn internally;

Fig. 13 is a view similar to Fig. 12 but showing the manner in which the pocket may be worn externally;

Fig. 14 is a section taken on lines 14-14 of Fig. 13 showing the manner in which the pocket, when worn externally, affords complete coverage of the side opening of the garment; and

Fig. 15 is a section taken on lines 15-15 of Fig. 13 showing the manner in which the pocket may be supported when worn externally of the garment.

Referring to Figs. 1, 3 and 4, one form of my invention is shown as adapted to a coverall work-garment or the like. Said garment comprises a slack 20 and a blouse 21. A side opening 22 at each side of the slacks provides a drop seat 23 and a front panel 24. As indicated in Figs. 3 and 4, the blouse is adapted to fasten to the slack by buttoning internally thereof, and said blouse is provided with false belt portions 25, 26, which are hingedly secured to the blouse and may be brought downwardly, see Fig. 5, to cover the button connections between the blouse and slacks for improvement in appearance and protection against catching the buttons against machinery, etc. when the garment is used as a work garb.

Front panel 24 has a waist-band 27, and drop seat 23 has a cooperating waist-band 28; the respective waist-band portions button together at the sides of the garment when the garment is worn.

The side openings are defined by plackets 29 which may be straps of material, doubled, and securely sewed to the front panel and drop-seat portions of the garment at the side seams thereof to provide a slit opening at each side. The placket portions overlie each other when the garment is worn, see Fig. 6.

Such placket construction is conventional and to prevent the side opening from gaping and exposing the body or undergarment of the wearer, it is conventional to employ fastening means such as zippers to secure the side openings.

The present invention affords means whereby the side opening can be fully and trimly closed without the use of fastening means, and in a manner which additionally affords ventilation of the garment at the side openings thereof.

My invention includes the use of a fabric frontispiece or shield 30 of substantially rectangular form which is secured along one of its side edges to one of the halves of the placket. If, as shown, the pocket is sewn to that portion which is sewed to the drop seat of the garment, the shield extends forwardly in overlapping relationship with the front portion of the garment; if the relationship is reversed, the shield would extend rearwardly, to cooperate with the rear portion of the garment. In either case, the shield may be worn internally or externally of the garment, as later described. Means are provided to support the upper free edge of the frontispiece or shield, as will later appear.

Functional advantages are obtained by forming the shield as an integral pocket unit, thereby combining utility with the primary objective of providing a buttonless side closure for a garment.

In the embodiment of the invention disclosed in Figs. 1 through 7, the rear waist-band portion 28 of the slack 20 is brought forwardly to overlap the front waist-band portion 27 to a substantial extent, see Fig. 5. The shields 30, il-

lustrated as pockets, are secured at their rear edge to the rear component of the placket 29, as shown in Figs. 3 and 6, and are unsecured to the forward portion of said placket. The pocket 30 is secured along its upper edge to the forwardly projecting portion of rear waist-band 28, see Figs. 4 and 5, and therefore overlies the thigh 10 of the wearer. When the garment is worn, the body contours bring the pocket into a snug relationship with respect to the front portion of the slack, thereby preventing any exposure of the body.

As shown in Figs. 3 and 4 either the front or the seat portion of the garment may be lowered without interference from the pocket for the reason that the said pocket is secured only to the rear portion of the garment.

By reason of the securement of the pocket or shield to the placket portion only along one side edge of said shield, the same may be worn either internally or externally of the garment and appropriate means are provided to support the upper free portion of the pocket or shield when the same is worn externally. Said means may include a cooperating button or buttonhole appropriately located.

In Fig. 4 there is shown a button 31 on the blouse 21, and buttonholes 32, 33, respectively on the pocket 30 and waistband 27. The pocket 30 buttons on to the same button 31, thereby firmly supporting the pocket 30.

When the pocket is worn externally, a button 34 on the underside of false belt 25 of blouse 21 buttons through buttonhole 32 on pocket 30 to support the same. The false belt 25 conceals the upper edge of the pocket when the pocket is worn externally.

In the embodiments of Figs. 8 through 15, an improved form of pocket and support means is shown as employed in a skirt, although it is obvious that the same may be applied to an individual slack or the combination of slack and blouse shown in Fig. 1. The skirt 40, see Fig. 8, has but a single side opening 22 provided by an appropriate placket, and the waist-band 41 of said skirt fastens at or adjacent the side opening of the garment.

The pocket 42 is secured only at the rear component of the placket 29, and the extent of securement may be for a distance less than the total length of the side opening, as clearly appears in Fig. 11. The pocket is not fixed to any waist-band portion, and for that reason the upper edge thereof is not substantially straight, as in the previous embodiment, but has a forward and upward contour, see Fig. 12, to bring the upper edge of the pocket 42 at approximately the upper edge of the waist-band 41. The upper free corner of the pocket is provided with a button-hole 43 and the waist-band has a button 44 for cooperation with said buttonhole. When the pocket is worn internally of the garment as shown in Fig. 8, the pocket is supported at said upper free edge by buttoning the same to the button 44.

To support the pocket when it is worn externally of the garment, as shown in Fig. 13, I provide on the waistband of the garment a tab 45 having a button 46 as illustrated, the said button facing the front of the garment as shown in Fig. 9, when the pocket is worn internally. When the pocket is worn externally as shown in Figs. 13 and 15, the pocket is unbuttoned from the button 44 and brought outwardly through the side opening to the Fig. 13 position and the tab 45 is brought

upwardly and outwardly over the waistband, see Fig. 15, whereupon the pocket is buttoned to the button 46 of said tab, thereby affording adequate support for the pocket at its said upper free edge.

As clearly appears in Fig. 11, the extent of securement of the pocket 42 to the placket 29 may be less than the total length of the side opening defined by said placket, thereby providing additional space at the bottom of the pocket, which forms an opening for ventilation of the garment. However, the principal means for ventilation, as in the Fig. 1 embodiment, is between the pocket and the thereto unattached placket portion.

Whereas I have described my invention by reference to specific forms thereof, it will be understood that many changes and modifications may be made provided they do not depart from the scope of the claims.

I claim:

1. In a garment having a side opening and a front and rear waistband portion adapted to fasten at or adjacent said side opening, a buttonless side closure comprising a unitary pocket secured at its rear edge to the rear side portion of the garment at a position lower than the rear waist band and extending forwardly in overlapping relationship with the front portion of the garment, the extent of securement of said pocket at its said rear edge being less than the length of the side opening of the garment, whereby said pocket may be brought to a position where it overlaps the front of the garment externally thereof while maintaining the closure of said side opening, and means for removably securing the pocket, at its upper forward corner portion, optionally to the under or outer sides of the garment at its front waist band portion.

2. In a garment having a side opening and a front and rear waistband portions, a side closure comprising a pocket secured at a side edge to one side portion of the garment and extending in overlapping relationship with the other side portion of the garment, whereby the pocket may be brought through the side opening to be worn optionally internally or externally of the garment, a buttonhole at the upper corner of the pocket, a button on the waistband of the garment for cooperation with said buttonhole to support the pocket beneath the front portion of the garment and a tab secured to said waistband on the inner surface thereof and adapted to be brought outwardly over said waistband to lie over the front of the garment, said tab having a button for cooperation with the buttonhole of said pocket to support the same when the pocket is worn externally of the garment.

3. In a garment in which openings at the upper sides thereof provide a front portion and a drop seat portion, a closure for the respective side openings, each such closure comprising a pocket secured at its rear edge to the forward edge of the drop seat of the garment at the sides thereof and extending forwardly for overlapping relationship with the front portion of the garment, the extent of securement of said pocket to the seat portion of the garment being slightly less than the length of the side opening, whereby said pocket may be brought outwardly through said side opening to overlie the front portion of the gar-

ment or, optionally, positioned beneath the front portion of the garment, and means whereby the free, forward portion of said pocket may be supported by attachment to the front portion of the garment either beneath the latter or in overlying relationship therewith.

4. In a garment having a side opening, and a side-opening waistband, by means of which the garment, at least at one side, is divided into a front and rear portion, closure means for said side opening, comprising a pocket structure secured at a portion of its upper horizontal edge to one of said garment portions, and secured at one, only, of its side edges to the edge of the side opening at the said garment portion and extending into overlapping relationship with the other of said garment portions; the securement of the side edge of the pocket to the side portion of the garment extending from a point beneath the waistband down to, but not substantially beyond, the bottom of the side opening to permit the pocket to be brought out through the side opening to overlie the portion of the garment with which it is in overlapping relationship, and means on the last-named garment portion to attach the free upper corner portion of the pocket to the garment in either the internally or externally worn positions of the pocket.

5. In a garment having a waistband and a placket-provided side opening, means for preventing exposure of the body or undergarments at said side opening, comprising a pocket structure of substantial width and a length greater than the length of the side opening, said pocket having the usual substantially vertical access opening, said pocket being secured at its vertical edge adjacent its access opening along one edge, only, of said placket-provided side opening, the uppermost portion of said side edge of said pocket not extending above the lowermost edge of said waistband; the upper edge of said pocket being unsecured to any garment portion and sloping upwardly to a point where the upper corner of the pocket remote from its secured vertical edge is in overlapping relationship with the waistband; the pocket thus being capable of wear either outside of or internally of, the garment, and means for removably securing said upper corner of the pocket to the garment in either of its said locations.

6. In a garment having a waistband and a side opening, means for preventing exposure of the body or undergarment at said side opening comprising a reversible pocket of substantial width and a length greater than the length of the side opening, said pocket having the usual substantially vertical access opening and secured at its vertical edge adjacent the access opening along the rear edge only of said side opening of the garment, and means for connecting the top of the pocket with the front portion of the waistband at the inner or outer face thereof, the pocket being movable through the side opening from the interior to the exterior and from the exterior to the interior, whereby the pocket may be worn outside or inside of the garment with the access opening accessible exteriorly of the garment in either position of the pocket.

MURRAY KAY.
